UNITED STATES PATENT OFFICE.

HUDSON BOGARDUS, OF NEW YORK, N. Y.

INTERCONVERTIBLE BOX, BRACKET, &c.

SPECIFICATION forming part of Letters Patent No. 249,823, dated November 22, 1881.

Application filed May 23, 1881. (Model.)

To all whom it may concern:

Be it known that I, HUDSON BOGARDUS, a citizen of the United States, residing in the city, county, and State of New York, have invented certain Improvements in Interconvertible Boxes, Brackets, and other Articles, of which the following is a specification.

In the accompanying drawings, Figures 1 to 4 are different views of a box, and Fig. 5 is a view of the separate pieces employed in its construction. Fig. 1 is a front elevation of the box. Fig. 2 is a side elevation thereof. Fig. 3 is an end elevation, and Fig. 4 is a vertical mid-section taken along the line 4 4 in Figs. 1 and 3. Fig. 6 is a side elevation of one section or half of the box used as a wall-bracket.

Referring to these figures, *a a* are the larger front and back boards or plates. *b b* are the smaller ones. *c c c c* are the four side pieces, and *d d* are the end pieces. These pieces are all cut, by preference, from thin boards of wood in any desired design. Two pieces, *c c*, and one of each of the other pieces combined together form a bracket, *A*, (shown in Fig. 6,) and two brackets, *A*, put together form a box, *B*, (shown in Figs. 1 to 4.)

Referring to Fig. 5, each piece *a* is cut with two open-ended slots, *a'*, on opposite sides, and on the same sides at the opposite corners from which these slots commence are two rabbets, *a''*. At one end is formed a spring-catch, *e*, consisting of two narrow and elastic projecting strips or tongues formed in one piece with the board *a*, and separated by a saw-kerf. Near the ends these strips are swelled or widened at *e'*, and contracted at *e''*, so as to form a wipe or latch, whose use will be explained hereinafter. Each piece *b* has also two open-ended slots, *b'*, inverted relatively to those in *a*, and it has also a closed slot or socket, *b''*, arranged at right angles to the slots *b'* and adjacent to one side or edge. Each piece *c* has two open-ended slots, *c'* and *c''*, on opposite edges and turned in opposite directions. It has also a hole or socket, *c'''*, a spring-latch, *f*, (which answers to one of the strips forming the latch *e*, already described,) and a notch or socket, *f'*, adapted to receive the latch *f* of another piece, *c*, as shown in Fig. 2. Each piece *d* has a broad projection, *d'*, on its first edge corresponding to the slot *b''*, in which projec-

tion is formed a slot or notch, *g*, corresponding to the latch *e*. On the opposite edge is a notch, *g'*, also corresponding to the latch *e*. On its opposite ends are projections *d''*, which correspond to the sockets *c'''*, and there are also other notches around its edge, which will be referred to hereinafter.

The parts are put together thus: The front piece, *b*, is connected to the side pieces, *c*, by sliding them together at their corners at right angles, the slot *c'* receiving the piece *b*, and the slot *b'* receiving the piece *c*. The piece *d* is then connected by thrusting it between the side pieces, *c*, toward the piece *b*, springing the free edges of the pieces *c* apart to admit the passage of the projections *d''*. The projection *d'* enters the slot *b''*, and the side pieces, *c*, being brought together again, the projections *d''* enter the sockets *c'''*. The back piece, *a*, is then slid on, its slots *a'* embracing the pieces *c*, and the slots *c''* embracing the piece *a*. All are now locked firmly together, and the bracket *A* is formed. To form a box for inclosing or packing articles, two of these brackets, exactly alike, are slid together, the back piece, *a*, of one bracket sliding across the front piece, *b*, of the other until the latches *e* enter the slots *g* and the latches *f* enter the recesses *f'*, as shown best in Figs. 1 and 2, when they are connected so firmly together that a strong pull is necessary to separate them. The rabbets *a''* narrow that portion of the piece *a* sufficiently to permit it to pass between the projecting edges of the pieces *c c*.

My box is especially adapted to be used as a packing-box for clocks. For this purpose I provide three extra pieces, *h*, *h*, and *i*, as shown in Figs. 7 and 8, of which Fig. 7 is a front elevation of one bracket *A*, inverted, and containing a clock, *C*, and the pieces *h*, *h*, and *i*; and Fig. 8 is a side elevation of these pieces removed. These pieces are designed to lock into the box and to confine the clock *C* in place therein during transportation. Each piece *h* has a downwardly-projecting arm, *j*, at whose end is a shoulder, *j'*. These arms *j* enter notches *j''* in the piece *d*, (see Fig. 5,) and the shoulders *j'* take under the piece *d*, so that the pieces *h* cannot be lifted while they are engaged. Each piece *h* has also two slots, *h'* and *h''*, Fig. 8, and the piece *i* has two slots,

i', which may interlock with either of the slots *h*' and *h*'''. In these figures the piece *i* is shown as in the slots *h*', so as to leave room for the clock *C* between it and the arms *j*. The clock 5 is placed on the floor *d*, the pieces *h h i* are put together and slipped down over it, their arms *j j* being passed into the notches *j*'' *j*''' and pressed down until the shoulders *j' j'* engage the floor *d*, when the clock will be confined 10 firmly in place. The second bracket *A* is then connected to the first, as shown in Figs. 1 to 4, whereupon, with a suitable wrapping, the whole is ready for shipment. The purchaser reverses this process in removing the clock, 15 and then, by proceeding as follows, he makes of the box a handsome bracket-case for the clock. He places the piece *i* in the slots *h*''', pushes the pieces *h h* toward the floor-piece *d*, inverts the half-box *A* to form a bracket, sets 20 the clock on the floor *d* thereof, places the other bracket *A* above it, and engages its latch *e* with the notch *g*' at the back of said floor-piece *d*, (see Fig. 5,) and hangs the whole on the 25 wall, when it appears as shown in Fig. 9, which is a front elevation. The pieces *h h i* now form an addition to the ornamentation of the lower bracket *A*.

My invention may also be adapted for holding or displaying other articles for sale or use. 30 Figs. 10 and 11 show it as a stationery-box, and Figs. 12 and 13 as a bottle-receptacle.

Fig. 10 is a plan of the stationery-box empty, and Fig. 11 is a front elevation thereof, in section, cut on the line 11 11 in Fig. 10. For this 35 use I employ the bracket *A* and three additional pieces, *m* and *n n*. The piece *m* rests on the floor *d* and has a latch, *l*, on each end or side, projecting below the floor through notches *l' l'* therein, (see Fig. 5,) and having a shoulder which bears upwardly against the floor, preventing the lifting of the piece *m*. This piece also has two slots extending upward from its bottom edge, and into these slots fit the pieces *n n*, which have interlocking slots extending from their upper edge downwardly. The pieces *m n n* are put together, the back piece, *a*, slid out, the sides *c c* sprung apart slightly, the latches *l l* pressed downward through the notches *l' l'*, the sides *c c* brought 50 together again, and the piece *a* replaced. Four compartments are thus formed, a large back compartment, *D*, suitable for holding paper, two front side compartments, *E E*, for holding envelopes, and a front central compartment, *F*, which may contain an inkstand. The pieces *n n* may be notched on their top edges to serve 55 as a pen-rack.

Fig. 12 is a plan of my box adapted for holding and displaying bottles, such as perfumery bottles, two of which are shown in it; and Fig. 13 is a vertical section thereof cut along the line 13 13, Fig. 12.

In addition to the bracket *A*, I employ three special pieces, *p p* and *q*, to form a bottle-rack. 60 Each piece *p* has two straight sides, which fit against the pieces *d* and *a*, and a downward projection, *p'*, at its back, which passes through

notches *p''* in the floor-piece *d*, and has a shoulder which takes under the same and prevents the lifting of the piece *p*. Each piece *p* has also 70 two slots, *q'*, one entering it horizontally, the other entering it vertically and downwardly. The piece *q* may enter either of these slots, and has coinciding slots which interlock with them. It has several sockets, *q'' q''*, for receiving the 75 necks of as many bottles, the sides of these sockets consisting of elastic tongues, so that the bottles can be inserted and removed by pressing them into the sockets, these tongues springing apart to admit them. The piece *q* 80 is put into the horizontal slots *q'* in the pieces *p p*, and the bottles are placed in the rack thus formed. The piece *a* is removed from the bracket *A*, the rack is slipped into place, and the piece *a* replaced. The second bracket *A* 85 being applied, the whole is ready for wrapping and shipment. When displayed in stores for sale the bottles may be removed from the rear side of the rack and stood on the piece *q*, as shown in dotted lines in Fig. 13. When the 90 bottles have been removed the piece *q* may be put in the vertical slots *q'*, and the receptacle inverted and used as a bracket, when this piece will serve as an ornament.

My box is well adapted for use as a cigar- 95 box, and if it is desired that it be left open on a counter for the sale of the cigars the pieces *a*, or one of them, may be made to slide off independently of the remainder of its bracket *A*, which may be accomplished by reversing the 100 slots *a' a'* and *c' c'*, causing them to extend from the opposite sides and in the opposite directions.

My invention is susceptible of considerable modification without departing from its essential 105 features, and I do not desire to limit myself to the exact form and construction shown. Among other modifications the latches *f f* may be omitted, or the latch *e*, instead of being placed in the middle, may be divided, and one 110 of its tongues or strips may be formed at each side, the projection *d'* being likewise divided and correspondingly arranged.

The part or structure *A* which I have hereinbefore referred to as a "bracket" is obviously 115 not essentially or necessarily a bracket, that name having been adopted by me in want of a more comprehensive one, since it may be so modified in design or proportion as to be incapable of use as a wall-bracket without departing from its essential construction. When 120 two of these brackets are united to form a box, *B*, it is only necessary that they should conform to each other in the dimensions of their interlocking parts so as to fit together, and 125 that their sides *c c* should conform to each other in outline to a greater or less extent, according as the box is desired to be more or less closed or imperforate. In making the sides *c c* for an imperforate box, I may cut the two 130 pieces which are to fit together edge to edge from one board with a scroll-saw.

I claim as my invention—

1. A receptacle consisting of the combina-

- tion of a bottom piece having projections from its edges with side pieces having sockets coinciding with and receiving said projections, each side piece having also a vertical slot near 5 each end extending from either its top or bottom edge about half-way to the opposite edge, and the slots at adjoining ends of contiguous side pieces extending in opposite directions, and being interlocked with each other, there- 10 by forming a receptacle whose bottom piece is confined between the side pieces, and whose side pieces overlap at the corners, are there interlocked, and project below the bottom, sub- stantially as set forth.
- 15 2. The combination of two receptacles, A A, each consisting of pieces forming the sides, and joined together by interlocking vertical slots, with their ends projecting beyond the corners, and of a piece forming the bottom fast- 20ened between them, one side piece on each re- ceptacle being prolonged beyond the others, and of such width as to fit between two of the projecting ends of the side pieces on the other receptacle, and the two receptacles being other- 25 wise conformed to each other, whereby when they are united they will form a closed box, B, substantially as set forth.
3. The combination of two receptacles, A A, each consisting of sides and a bottom joined 30 together, and each provided with an elastic elongation from one of its sides entering a socket formed in the bottom of the other, and serving as latches to fasten the two recepta- 35 cles together to form a closed box, B, substan- tially as set forth.
4. A wooden receptacle, A, having a spring- 40 latch, e, consisting of opposite elastic tongues made integral with one of the pieces compos- ing the receptacle, and formed with a contract- ed neck, e'', and enlargement e', in combination 45 with another receptacle having a socket into which said spring-latch enters when the two receptacles are fitted together, substantially as set forth.
- 45 5. A receptacle consisting of a back piece, a, side pieces, c c, and front piece, b, provided at their ends with vertical slots, whereby they may be slid together and interlocked at the corners of the receptacle, in combination with 50 a floor-piece, d, confined between them and locked in place by projections from its edge enter- 55 ing sockets in the said other pieces, sub- stantially as set forth.
6. The combination of back piece, a, having slots a', front piece, b, having slots b', and closed
- slot or socket b'', side pieces, c c, having slots c' and c'', and socket c''', and floor-piece d, hav- 60 ing projections d' and d'', substantially as set forth.
7. A receptacle consisting of pieces a b and c c, joined together rectangularly at their cor- 65 ners, and floor-piece d, confined between them and having projections entering sockets in them, in combination with a second like recep- tacle, the two capable of fitting together to 70 form a closed box, and with means for fastening them together substantially as set forth.
8. A bracket consisting of pieces a b and c c, joined together rectangularly at its corners, 75 and floor-piece d, confined therein, and having projection d' passing through piece b, and pro- vided with slot g, in combination with a second similar bracket capable of fitting to the first and forming with it a closed box, and having a 80 spring-latch, e, formed on its piece a, capable 85 of engaging said slot g when the two brackets are put together, and thereby serving to fasten them together, substantially as set forth.
9. A bracket consisting of pieces a b and c c, joined together rectangularly at its corners, 80 and floor-piece d, confined between the sides, in combination with a second like bracket, the 85 two being capable of fitting together and form- ing a closed box, in combination, also, with elastic latches f f, and sockets f' f' therefor formed in the pieces c c, and adapted to fasten 90 the two brackets together, substantially as and for the purposes set forth.
10. The combination, with a box, B, formed 95 of two brackets, A A, capable of fitting to- gether, of interlocking pieces capable of at- tachment to one of said brackets and adapted to hold goods or articles in place therein for shipment, and to serve as ornamental additions thereto when used as a bracket, substantially 95 as set forth.
11. The combination, with a box, B, formed 100 of two brackets, A A, capable of fitting to- gether, of interlocking pieces h h and i, adapted to confine a clock or similar article in place 100 within the box during shipment, and capable of serving as ornaments to one of the brackets when used as such, substantially as set forth.
- In witness whereof I have hereunto signed my name in the presence of two subscribing 105 witnesses.

HUDSON BOGARDUS.
